(57) **CLAIM**

The ornamental design for a vehicle display screen or portion thereof with an animated graphical user interface, as shown and described.

DESCRIPTION

FIG. 1 is a front view of a first image in a sequence for a first embodiment of a vehicle display screen or portion thereof with an animated graphical user interface;

FIG. 2 is a front view of a second image thereof;

FIG. 3 is a front view of a third image thereof;

FIG. 4 is a front view of a first image in a sequence for a second embodiment of a vehicle display screen or portion thereof with an animated graphical user interface;

FIG. 5 is a front view of a second image thereof; and,

FIG. 6 is a front view of a third image thereof.

The appearance of the animated graphical user interface sequentially transitions between the images shown in FIGS. 1-3, and in FIGS. 4-6.

The process or period in which an image transitions to another forms no part of the claimed design.

The broken lines showing a display screen or portion thereof, forms no part of the claimed design.
